LENS

Hugo Magi, Etobicoke, Ontario, Canada, assignor to
Dominion Auto Accessories Limited, Toronto, Ontario,
Canada

Filed Sept. 24, 1969, Ser. No. 19,288

Term of patent 14 years

Int. Cl. D26—06; D12—99
U.S. Cl. D48—16

In the drawing, FIG. 1 is a perspective view of a lens showing my design;

FIG. 2 is an enlarged cross-sectional view of the lens of FIG. 1, taken at the line 2—2 in FIG. 1; and

FIG. 3 is a greatly enlarged longitudinal sectional view of one-half of the lens of FIG. 1, taken at the line 3—3 in FIG. 1, the other half having the same but inverted section.

I claim:

The ornamental design for a lens, as shown and described.
